UNITED STATES PATENT OFFICE.

GEORGE F. KIME, OF ELDORADO, KANSAS.

WAGON-BODY.

1,328,999.

Specification of Letters Patent. Patented Jan. 27, 1920.

Application filed February 16, 1918. Serial No. 217,542.

To all whom it may concern:

Be it known that I, GEORGE F. KIME, a citizen of the United States, residing at Eldorado, in the county of Butler and State of 5 Kansas, have invented certain new and useful Improvements in Wagon-Bodies, of which the following is a specification.

My invention relates to wagon bodies and more particularly to combination bodies 10 which may be used as grain boxes, flat hay racks, and header barges.

The object of my invention is to provide a wagon body or a body for use on farm wagons having sides and ends connected by 15 hinges to the floor or bed of the body and which may be secured in a vertical position forming a grain box and which may be let down in a horizontal or flat position forming a hay or bundle rack.

20 Furthermore, the object of my invention is to provide a wagon body having supports connected to the floor thereof and extending outwardly on each side to support the sides of the bed when in a horizontal position.

25 Finally, the object of my invention is to provide a wagon body having a removal side and end pieces which are secured by stays on the upper edge of the side and end, the end pieces being of a greater width at 30 one end than at the other, thereby forming a grain barge in which one side is of greater height than the opposite side.

With the foregoing and other objects in view, my invention consists in the details of 35 construction and in the arrangement and combination of parts to be hereinafter more fully set forth and particularly pointed out in the claims.

In describing my invention in detail, reference will be had to the accompanying 40 drawing, forming a part of the specification wherein like characters denote corresponding parts in the several views in which:—

Figure 1 is a top plan view.

45 Fig. 2 is a sectional view on the line 2—2 of Fig. 1.

Fig. 3 is the side elevation.

Fig. 4 is a sectional view on the line 4—4 of Fig. 1.

50 Fig. 5 is the end elevation.

Fig. 6 is a sectional view on the line 6—6 of Fig. 3.

Fig. 7 is a sectional view showing the end construction of the header barge.

55 In the drawing 1 indicates the bottom or

bed of the wagon body which is provided with end supports 2—2 suitably secured at each end. Supports 3—3 are secured to the bottom intermediate its length and extend beyond the side of the bed and which are 60 connected at the outer ends by cross pieces 4—4, the cross pieces 4—4 providing supports for the sides of the body when in a horizontal position.

I secure end pieces 5—5 on each end of the 65 bottom by means of angle brackets 6—6 which rigidly support the end pieces in a vertical position. Extensions 7—7 are connected at each end of the end pieces 5 by hinges 7'—7'. Sides 8—8 are secured to the 70 bottom 1 by hinges 9. To the sides 8, I secure extensions 10 by means of hinges 11, the hinges being so arranged that when the extension 10 is not in use it is folded down on the inner side of the side 8 and when in 75 use as a hay rack, the sides 8 form an extension of the bottom and the sides 10, the outer side pieces. The end extensions 7 are provided with hinged keepers 12 whereby the end extensions may be secured parallel 80 with the side pieces 8 when the body is being used to convey loose grain.

In the construction of my improved wagon bed when used for the grain barge I provide end pieces 13 which terminate in 85 the point 14 at one side and are secured on the upper edge of the end pieces 5 by means of the loop support 15 through which the end pieces 13 are inserted.

A side piece 16 is rigidly supported on the 90 upper edge of one side of the wagon bed by suitable supports which construction provides a barge in which one side is of greater height than the opposite side.

In the use of my improved wagon body 95 the sides and end pieces being secured in a vertical position by means of the end extension 7 folding parallel on each end of the side pieces and the keeper 12 being secured by means of suitable fasteners, the sides and 100 ends are rigidly held together to form a tight grain body.

When it is desired to use my improved wagon body as a hay or grain rack, the sides of said body are lowered to a horizontal 105 position, said side pieces resting on the supports 4 and the end pieces remaining in a vertical position. This construction provides for the flat bottom hay or grain rack for conveying hay or straw. In the arrange- 110

ment of my improved wagon body as a grain barge the side pieces 8 are let down in a horizontal position forming an extension of the bottom, and the side pieces 10 are elevated in a vertical position as shown in Fig. 6. Upon one of the side pieces 10, I secure the side piece 16 by means of a suitable support. The side piece 16 abuts against the inner edge of the end piece 13 10 which construction forms a grain barge as shown in Figs. 5 and 6 of the drawing.

It is believed that the construction and use of my improved wagon body will be fully understood from the foregoing description 15 it being noted that changes in the proportion and details may be made without departing from the scope of my invention.

What I claim as new and desire to secure by Letters Patent is:—

- 20 1. The combination in a wagon bed, of a bottom provided with hinged sides and rigid end pieces, said end pieces being provided with extensions adapted to fold parallel with said sides, and additional pieces pivotally connected upon the upper edge of the first mentioned side pieces, loop supports secured upon each rigid end piece, and end extensions adapted to be removably secured within said loop supports, substantially as 30 described.
2. In a combination wagon bed, a bottom, a support secured to each end of said bottom, supports secured to the bottom intermediate its length and extending beyond the 35 edge of said bottom, side pieces hingedly

secured to said bottom, an end piece secured to the bottom at each end thereof, said end pieces being provided with extensions adapted to fold parallel with said side pieces, an additional side piece hingedly secured to each of the before mentioned side pieces and adapted, when not in use, to lie parallel to said first named side pieces, a loop support secured to and upstanding from each of the end pieces, an additional side piece secured to one of the above mentioned additional side pieces, and an end piece removably secured within the above mentioned loop support. 40 45

3. In a combination wagon bed, a bottom 50 having side pieces suitably hinged thereto, an end piece rigidly secured to each end thereof, supports secured to the ends of said bottom, additional supports secured to said bottom intermediate the ends thereof and 55 extending beyond the sides of said bottom, the above mentioned side pieces being adapted to rest upon said second named supports when in a lowered position, loop supports secured intermediate the upper edge of said 60 end pieces, an additional side piece secured to one of the above mentioned side pieces, and a tapered end piece removably secured within said loop support.

In testimony whereof I have affixed my 65 signature in the presence of two witnesses.

GEORGE F. KIME.
